BRAKEDRUM COOLING DEVICE OR THE LIKE

Elvon C. John, 451 W. Dulles Road,
Des Plaines, Ill. 60016

Filed Dec. 6, 1967, Ser. No. 9,672

Term of patent 14 years

(Cl. D14—30)

FIGURE 1 is a front elevational view of a brakedrum cooling device, showing my new design;

FIGURE 2 is an end view thereof; and

FIGURE 3 is a rear elevational view thereof.

I claim:

The ornamental design for a brakedrum cooling device or the like, substantially as shown.
